UNITED STATES PATENT OFFICE

ALFRED L. BROWNE, OF SOUTH ORANGE, NEW JERSEY

VENTING APPLIANCE FOR HEATING SYSTEMS

Application filed April 1, 1931. Serial No. 526,892.

This invention relates to heating systems and appliances forming a part of such systems.

Objects of the invention are to provide novel arrangements whereby heating systems may be operated more efficiently and/or with a reduced number of parts.

In heating systems, for example, steam heating systems, employing radiators which are supplied from a boiler with heated condensable elastic fluid, it is desirable to vent air from each radiator to atmosphere, to prevent the annoying escape of the elastic condensable heating fluid from the system and also the consequent waste of the heat energy contained in it, and also to prevent accumulation of condensed liquid in parts of the system other than the boiler lest undesired and even unsafe lowering of the liquid level in the boiler result. In order to insure return of the liquid of condensation to the boiler, appliances such as boiler return traps, pressure-equalizing seals, pumps, have heretofore been employed.

By virtue of my invention, presently to be described, it is necessary to provide in the piping system to and from the boiler only the usual radiators and, for each radiator, a single venting appliance between the outlet of the radiator and its return pipe; this venting appliance serving automatically (1) to vent air with facility and at the desired rate from each radiator, (2) to prevent wasteful escape of heating fluid, and (3) to permit and cause prompt return of condensate to the boiler.

The venting appliance hereafter described is an improvement upon that shown in Figs. 1 and 2 of my copending application Serial No. 294,078, and may be substituted therefor in the heating system shown in Figs. 3 and 4 of the said copending application and described therein as well as in other systems.

Referring to the drawings, which illustrate what I now consider a preferred form of my venting appliance:

Fig. 1 is a sectional elevation of the venting appliance.

Fig. 2 is a detail sectional elevation of a

part of the appliance shown in Fig. 1 with added features.

Fig. 3 is a detail sectional elevation of a part of the appliance shown in Fig. 1 with a modification in the air-venting control.

Fig. 4 is a detailed sectional elevation of a part of the appliance shown in Fig. 1, with an additional modification in the air-venting control.

My venting appliance may, as stated, be employed in the heating system shown in Figs. 3 and 4 of my copending application Serial No. 294,078 and described therein. It may likewise be employed in other systems, some of which will be referred to hereinafter. I shall now first describe a preferred construction of the venting appliance and then indicate some of the various modifications that may be employed within the scope of the invention as defined by the appended claims.

The venting appliance shown in Fig. 1 comprises a valve casing which is sealed except at three passages. One of these passages, 10, admits air, steam, and water of condensation to the interior of the casing. Another of the passages, 11, discharges water of condensation from the casing. The other passage, 12, discharges air from the interior of the casing to the atmosphere. The valve casing shown comprises the body portion, 13, which is externally screw-threaded to receive the nut, 14, which holds the valve spud 15, tightly seated in the inlet end of the passage, 10, internally screw-threaded at the outlet end of the passage 11 to receive a discharge or return pipe or conduit, and internally screw-threaded to receive the valve bonnet, 16, which is, in turn, internally screw-threaded to receive the valve member, 17, and the subbonnet, 18, the latter being provided with a screw-threaded vent opening, 19.

Means are provided within the valve casing, called into action by the entrance of steam into the casing, for closing the passage, 12. The means shown comprise the following structure: The valve head, 20, adapted to seat in the valve seat provided in the valve member, 17, is secured to and carried by a sealed, hollow metallic container, 21, having a comparatively flexible bottom or diaphragm, 22,

and containing a volatile fluid. The bottom or diaphragm, 22, rests upon or abuts against a stationary support, 23. These parts are so designed and constructed as to operate as follows: In the absence of steam within the valve casing, the pressure of the volatile fluid within the container, 21, is insufficient to force the diaphragm, 22, downwardly to such an extent as to move the valve head, 20, 10 against its seat in the valve member, 17. However, when steam enters the valve casing, it contacts through orifices, 33 and 34, with the thermostat, 21, 22, imparting heat thereto, causing the volatile fluid to expand 15 and thus causing the diaphragm, 22, to bulge downwardly to such an extent as to close the valve head, 20, on its seat. The casing, 23, which houses the thermostat, 21, 22, is threaded at its upper end and adapted to thread 20 into the upper portion of bonnet, 16, as shown. The casing, 23, is provided with orifices, 33, at its upper portion, and also with orifices 34, through the floor or bottom. These orifices, 33 and 34, permit the thermostat, 22, to be in 25 restricted communication with the interior of the valve casing 13, 16. The orifices 33 may be eliminated entirely and one or more orifices 34 only may be used. The casing, 23, also controls or limits lateral movement of 30 the member, 21, accurately and to a minimum extent.

Means are provided also for preventing the escape of water of condensation from the valve casing through the passage, 12. The 35 container, 21, above described, acts not only as a thermostat but serves also as a float. If and when water collects and its level rises within the valve casing, this float, 21, is raised by the rising water and forces the valve head, 20, firmly against its seat before the water 40 level reaches the passage, 12.

There are also provided means for preventing the entrance of air into the valve casing through the passage, 12. One form of 45 such means is shown in Fig. 1, and is constructed as follows: The upper end of valve member, 17, is provided with an annular rib or seat, 24, upon which a valve disc, 25, rests. This valve disc permits the escape of air from 50 the interior of the casing, 13, 16, to atmosphere through the passages, 12 and 19, but when the pressure within the casing, 13, 16, is below atmospheric pressure, the valve disc, 25, prevents entrance of air into the casing, 55 13, through the passage, 12.

The valve disc, 25, is made of the desired thickness and weight for the purpose of providing any desired air venting resistance.

By using discs, 25, each of the properly 60 designed weight for its radiator, the steam circulation within the respective radiators can be balanced so that the complete heating of each radiator can be effected at approximately the same time, regardless of the difference in size of the radiators or their re-

spective nearness to or distance from the boiler.

Within the valve casing, 13, are provided also pressure responsive means for preventing the entrance of water, air, or steam 70 through the passage, 10, back into the radiator. These means include a specially-constructed check valve, consisting of a body or seat member, 26, to which there is pivotally connected a valve head or clapper, 27, at 28. 75 The neck of the check valve body, 26, protrudes through an annular orifice in the valve casing, 13. The neck of the check valve body, 26, is threaded to receive a lock nut, 30, in order securely and rigidly to fasten the 80 entire check valve member in place. A gasket, 29, may be provided in case the contacting surfaces between the valve body, 13, and the shoulder of the extension neck of the check valve casing, 26, are not machined to 85 an accurate, tight fit.

The check valve body is provided with a duct or port, 31, the upper end of which is parallel to and adjacent the spud port or passage, 10. The lower end of the duct 90 90 terminates at the annular rib or check valve seat, 32. It will be observed that the upper end of check valve port, 30, and the lower end of check valve port, 30, are at two different levels, the outlet end of the duct 30 being below the inlet thereto.

The valve appliance described above is not only applicable to the novel heating system disclosed in my said copending application but is also adapted to be applied to a standard gravity return vapor type of heating system, utilizing steam with marked advantages.

Such standard types of systems, last referred to, usually employ a boiler, a system 105 of supply piping for conveying steam to radiators through radiator inlet valves at the top of each radiator, each radiator being also equipped at its return end with a thermostatic valve or similar device. In such standard systems the return piping starts at the radiator return traps and terminates dry (above the water line of the boiler) at or near the boiler; from this point, boiler return traps, pressure equalizing seals, pumps, or 110 other means, are employed to effect return of the condensate back to the boiler and the liberation of all air from the system is also usually effected at this point. Such standard systems also commonly employ, in addition, a wet or dry pressure drip return, draining the end of the steam mains and connecting directly to the boiler return header.

In the application of this invention to a 125 gravity return system of heating, as described, all three systems of basement mains, namely, steam mains, dry return mains, and (wet or dry) pressure drip return mains, may be used. Boiler return traps, pressure equalizing loop seals, pumps, air venting traps or 130

devices, or other similar apparatus, may be dispensed with as unnecessary. The dry return may be dispensed with and the return risers may connect into the (wet or dry) pressure return, or they may connect back into the steam mains, either sealed wet or dry. These modifications in piping are possible as there is normally no air flow in the return piping system from this invention, and virtually no pressure differential between the supply and return piping systems.

The operation of my invention, as applied to a gravity return system having steam-supply means and separate return piping, is substantially as follows:

When steam is generated at the boiler, a very slight pressure is sufficient to cause the check valve clapper, 27, to open. This member is normally closed and quite delicately balanced against an annular valve seat, 32. This valve seat, 32, is virtually a line contact preventing the valve capper, 27, being held to its seat by grease or water adhesion and, furthermore, also preventing a pressure drop at this point under flow conditions as would occur if this valve member, 27, 32, had broad seating surfaces. Consequently, air, condensate, and steam can readily enter into the body, 13 and 16, of the trap through the inlet spud port, 10, and the check valve port, 31. Condensate immediately falls by gravity through the outlet port, 11, into the return system of piping. A very slight pressure within the valve body and bonnet, 13, 16, is sufficient to permit the free expulsion of air through the outlet port, 12, and thence through the venting port, 19, to atmosphere. This expulsion through the port, 12, may be retarded or accelerated by selection of the thickness and weight of the disc 25. The air, in escaping from the valve body, 13, and bonnet, 16, through the venting orifice, 12, is first compelled to pass through the orifices, 33, at the top portion of the thermostat casing, 23, or through its bottom orifices, 34.

When considerable steam pressure is carried and a radiator is nearly completely hot and there are present within the valve casing and bonnet, 16, air, hot condensate and steam in a state of considerable turbulence, orifices, 33 and 34, to a material extent act as a separator and buffer against extreme turbulence, insuring the expulsion of air only through the venting orifice, 12, without spitting or discharging condensate. Furthermore, the orifices, 33 and 34, tend to diminish any extreme vertical oscillation of the float member, 21, when and if there is condensate within the valve casing, 13, and bonnet, 16, in a state of turbulence caused by the intermittent venting of the valve, 20, and member, 21.

Following this initial heating up of a radiator or radiators upon a rising steam pressure, or if the radiator supply valve is opened during the existence of steam pressure, the

conditions then within the interior of this valve casing 13—16 subside to a point where in there is uniform pressure within the casing and a very slight intermittent venting of air and other non-condensable gases through 70 venting orifice, 12, upon a slight change in temperature around the float and thermostat, 21, and 22, of but a few degrees. This insures radiator efficiency, insofar as the expulsion of air and other non-condensable gases is concerned. The hydrostatic head caused by the outlet portion of the check valve conduit, 31, at the valve seat, 32, being lower than its inlet portion, 30, adjacent to the inlet port, 10, through the valve spud, insures a complete, 80 rapid, and continual drainage of the condensate from the radiator. Inasmuch as this hydrostatic head is materially more than is necessary to cause the valve clapper, 27, to open, it is apparent therefore that it is impossible to cause any rise of water within the radiator above the inlet port, 10, within the capacity of the trap. The condensate discharged within the valve body, 13, would therefore continually drain through the outlet port 11, or return connection of the casing. 90 From this point, the condensate would by the law of gravitation find its way back to the boiler. In addition to the condensate returning to the boiler within the return line 95 piping, there would in addition be present within this piping system, either air, or air and steam. The pressure of these gases within the return line piping would be practically the same as the pressure of the gases within 100 the radiator, with the following exceptions: Between each radiator and the return line, the check valve, 27, would offer some slight resistance, and the slight pressure drop within the entire heating system caused by the flow 105 of steam from the boiler to this trap would cause some slight additional difference in pressure. The check valve pressure differential would be constant. The pressure drop, due to steam flow, would vary somewhat, depending upon the size of the heating system and the design of its piping. The differences in this slight pressure differential would in effect amount to a hydrostatic head of one inch to possibly twelve inches in a large installation at the termination of the return piping where it connected to the return connection of the boiler. Therefore, beyond this slight quantity of condensation and small hydrostatic head, there would be no additional pressure differential and consequently no additional quantity of condensate held in suspension within the return line system, regardless of the particular steam pressure carried. Any additional devices to insure the return of condensate back to the boiler, particularly under pressure condition of operation, are unnecessary. Inasmuch as the air from each and every radiator, is directly vented through this invention at each radi- 130

ator, it is unnecessary to provide additional devices on or at the termination of the return main to vent the air from all the radiators.

If a radiator is turned off while steam is being circulated to other radiators turned on, steam from the radiators turned on, provided there is sufficient steam pressure being carried, would gradually find its way to the interior of the valve body and bonnet, 16, of the radiator turned off, due to the contracted or open position of the valve members, 20, 12. The check valve members, 27 and 32, being normally closed, would prevent the steam from heating the radiator turned off. Steam now being present within the valve casing, 16, and body, 13, would cause the thermostat, 21, 22, to close the venting valve 20, 12 exactly the same as in cases where the radiators were turned on. However if the radiator supply valve is opened on the radiator turned off, this radiator would heat virtually as fast as if this condition did not pertain, for the following reasons: When a radiator inlet valve is opened, the conditions within that particular radiator and other radiators would be the same in respect to pressure. The weight of the air within the radiator, being greater than the corresponding head of steam, would therefore cause a slight opening of the delicately balanced check valve, 27. Inasmuch as the check valve, 27, of this radiator would have the same resistance as that of the check valve clapper, 27, of any other radiator, it would open, due to the fact that there would be a slight pressure drop between this check valve clapper, 27, and any other check valve clapper, 27, from which steam was being supplied to the interior of this trap. When the radiator valve is opened, the pressure on the check valve clapper, 27, would initially be exactly the same as the pressure at the radiator inlet valve, due to the lack of any pressure drop between the inlet and outlet of the radiator because of the lack of condensing of steam within the radiator, while, on the other hand, steam being supplied as previously described to the interior of this trap from another radiator, would at the point of the check valve clapper, 27, of that radiator, be at a lower pressure than at the check valve clapper of this radiator, due to the fact that that radiator would necessarily have some pressure drop between its inlet and outlet because of the condensing effect of the radiator.

The combination of these forces is therefore more than sufficient to cause a slight opening of the clapper, 27, when any radiator is turned on while the vent within the casing 13-16 at that particular radiator is closed, due to steam from another radiator. The instant that this clapper, 27, opens, a quantity of air, or air and condensate, enters the valve casing, 13, immediately causing a slight drop in temperature within the valve body, 13, and

bonnet, 16, which is sufficient to affect the thermostat 21, 22, and cause the valve member, 20, 12, to open with a consequent venting of air from the radiator turned on. Thereafter, the formation of condensation within this radiator will, in its flow through port, 10, and port, 31, cause the check valve clapper 27, to be more or less continuously open. With this condensate, air will be more or less continually discharged within the valve body, 13, 75 16. The continual cooling effect of this action is sufficient to permit a rapid and complete heating in spite of the slight interference caused by steam from other radiators turned on. 80

In any case where the return from any given radiator turned off terminated wet (below the water line of the boiler) without any other radiator connecting into this return, then if the boiler pressure was sufficient and the level of this valve sufficiently close to the water line, condensate would back up within this particular valve and cause the float, 21, to rise and effectively close the venting valve members, 20 and 12. When this particular radiator was turned on and consequently pressure conditions equalized, this water would recede to its normal level, approximately boiler water line. 90

An additional and quite desirable feature 95 is embodied in my venting appliance shown in Fig. 1. The thermal-responsive member 21, as stated, comprises a sealed hollow metallic container having a comparatively flexible bottom or diaphragm 22 and containing a volatile fluid. The design and construction are such that expansion of the volatile fluid, under rise of temperature, as described, closes the valve 20-12 to prevent escape of steam. Also, in view of the fact that the member 21, 22 serves as a float, the valve 20-12 closes automatically if and when liquid rises in the casing 13, 16, so that escape of liquid through the port 12 is prevented. In addition, the container 21, 22 is so constructed and designed 100 that normally the pressure within it is sub-atmospheric, i. e. a partial vacuum exists in the container 21, 22. As a consequence, if the container 21, 22 should spring a leak, the diaphragm 22 will assume a flat or plane 115 position (instead of being convexed upwardly) and cause the valve 20-12 to close, thereby sealing the passage 12 and preventing the escape of any steam or water. 110

The device illustrated in Fig. 1 possesses 120 also other desirable features not yet described. Thus, a flat strip 35 of spring brass, or other suitable material, is sprung and seated at its opposite ends in undercut slots in the member 17 to prevent dislodgment of the 125 disc or flap 25 but yet to permit its unseating to permit controlled escape of air from the port 12 to the atmosphere. Furthermore, the member 17 is shown provided with lateral holes or apertures 36 to dis- 130

charge any drops of condensate laterally, or radially, and then downwardly to the metallic evaporating floor 37. When steam first enters the casing 13, 16, particularly if the radiator to which it is connected is turned on suddenly while pressure is carried, there may be a few drops of condensation formed on the general interior surfaces of the entire venting appliance. Should one or two drops of this condensate formed on the valve members 17, 20, be discharged through the valve orifice 12, effective evaporation of this small quantity of condensate is achieved without any discharge thereof through the final venting port 19.

As previously stated, one or more orifices 34, with or without orifices, 33, properly designed, effectively meter condensate into the container 23. The fewer the number of these orifices, or the smaller their size, the more effective this metering action will be. Also, any condensate that enters the container 23 is metered out at a rate depending upon the construction of the orifices 33 and 34. Consequently, the responsive action of the float member 21, up or down, opening and closing the valve members 20—12, may be so regulated as to be extremely slow and thus prevent spitting or discharge of condensate as commonly occurs in many air venting valves due to the rapid falling and rising of the condensate around the float member and the rapid and erratic movement of the float member caused by this turbulence.

My venting appliance may also be provided with means for muffling the expulsion of air which commonly and ordinarily produces a hissing sound in many forms of air-venting appliances. One form of such muffling means is shown in Fig. 2 in which the sub-bonnet 18 is provided with two annular screens, 38 and 40, of perforated sheet brass or other reticulated metal, between which is confined a quantity of pebbles 39, or other durable, steam-resistant, and heat-resistant particles. These provisions permit the escape of air but muffle the sound ordinarily incident to such escape.

The venting appliance is, of course, susceptible to modification. Thus, instead of selecting the size and weight of the disc or clapper 25 to control the escape of air from the port 12, the arrangement shown in Fig. 3 may be employed.

According to the construction shown in Fig. 3, the casing portion 16A corresponds to the casing portion 16 in Fig. 1 except that the screw threads for the sub-bonnet 18A are provided on the outside instead of the inside. The member 17A corresponds to the member 17 of Fig. 1 but is somewhat modified in construction as will now be noted. The member 17A, having the port 12A corresponding to the port 12 in Fig. 1, is internally screw-threaded in order adjustably to

receive a screw 41 which is provided with a T-shaped passage 43 communicating with the port 12A. The upper end of the screw 41 is conical to serve as a valve member and is provided with a slot for purposes of adjustment. The sub-bonnet 18A, provided with the tapped opening 19A corresponding to the hole 19 in Fig. 1, serves to grip between it and the upper end of the bonnet 16A, a flexible metallic diaphragm 125 having a valve member 44 adapted to be closed by the member 41. By inserting a screw driver through the opening 19A into the slot in the head of the screw 17A, and turning it in one direction or the other, the position of the valve member 17A with respect to the valve member 44 may be adjusted and set as desired. By virtue of this adjustment the time of opening and closing and the rate of air discharge through the valve 17A—44, with respect to the steam pressure may be regulated, adjusted, and set, as desired. Thus the heating of each radiator with respect to another, or others, can be readily controlled and at will.

These valve members 41, 44, are normally closed. When the pressure within the heating system exceeds atmospheric pressure, these valve members open due to the fact that the pressure in the casing 16A slightly lifts the diaphragm 125 and unseats the valve. The resistance to such opening may be varied by adjusting the valve head 41 in order to balance the circulation of steam to all radiators. When the pressure within casing 16A is less than atmospheric pressure, then the atmospheric pressure exerted upon the diaphragm 125 through the venting port 19A forces the valve member 44 tight against the valve head 41. Due to the fact that the area of the diaphragm 125 is many times greater than the actual venting area of the valve members 41 and 44, there results a tighter seating of the valve members 44 and 41 than results from the difference in pressure between the inside and outside of the valve 25 shown in Fig. 1. However, a diaphragm of this type, although tighter on vacuum, would require more pressure to open it to permit venting of air than is required by the previously described structure shown in Fig. 1.

The advantages of a free discharge of air and a very tight closing under a slight vacuum are both obtained with the construction shown in Fig. 4. In Fig. 4 the sub-bonnet 18B, having the opening 19B, corresponds to the sub-bonnet 18 of Fig. 1 or 18A of Fig. 3; the member 44A corresponds to the housing for the valve 25 as in Fig. 1 and serves also as a valve member corresponding to the valve member 44 of Fig. 3. In the arrangement shown in Fig. 4, the valve 41—44A is normally open and closes only when the pressure within the casing 16A is sub-atmos.

pheric. Being normally open, air can vent freely through these valve members 41-44A and lift the disc 25 and vent through the port 19B. When the pressure within the casing 5 16A is sub-atmospheric, i. e. a partial vacuum, the disc 25 closes as previously described in connection with Fig. 1. However, atmospheric pressure exerted through the vent port 19B upon diaphragm 125 causes 10 the whole member 44A to drop slightly and seat securely on the fixed valve head 41, giving under vacuum conditions of operation, the tight venting valve feature as described in connection with Fig. 3.

15 It will be noted (see Fig. 1) that the cross-sectional area of the duct 31, through which all fluid entering the casing at the inlet port 10 must flow, is very much less than the cross-sectional area of the outlet port 11 through 20 which the condensate discharged from the casing must flow. By virtue of this provision and relationship, objectionable water-plugging of the outlet port 11, or the return pipe connected thereto, is prevented.

25 The internally threaded discharge opening 19 (or 19A or 19B) may be closed by a plug (not shown) screwed therein when a system is to be converted from a vapor or steam system to a hot water heating system.

30 In accordance with the provisions of the patent statutes, I have herein described the principle of operation of my invention, together with the apparatus which I now consider to represent the best embodiments thereof, but I desire to have it understood that the apparatus disclosed is only illustrative and that the invention can be carried out by other means. Also, while it is designed to use the various features and elements in the combinations and relations described, some of these may be altered and others omitted and some of the features of each modification may be embodied in the others without interfering with the more general results outlined, and 45 the invention extends to such use.

What I claim is:

1. A venting appliance for steam heating systems and comprising in combination; a casing having an inlet port for admitting vapor, air, and condensate, an outlet port for discharging air, and an outlet port for discharging condensate; a one-way valve through which all fluid entering the casing through the inlet opening must flow, the interior of said casing being at all times in free communication with its condensate outlet port, heat-responsive means within said casing for substantially preventing discharge of heated vapor through the air discharge port, and liquid-level responsive means within the casing for substantially preventing discharge of condensate through the air discharge port.
2. A venting appliance for steam heating systems and comprising in combination; a

casing having an inlet port for admitting vapor, air, and condensate, an outlet port for discharging air, and an outlet port for discharging condensate; a one-way valve through which all fluid entering the casing 70 through the inlet opening must flow, the interior of said casing being at all times in free communication with its condensate outlet port, heat-responsive means within said casing for substantially preventing discharge 75 of heated vapor through the air discharge port, liquid-level responsive means within the casing for substantially preventing discharge of condensate through the air discharge 80 port, the liquid-level responsive means including a float, and means comprising a float chamber in communication with the interior of the casing for preventing surging of the float when condensate within the casing is in 85 a turbulent state.

3. A venting appliance for steam heating systems and comprising in combination; a casing having an inlet port for admitting vapor, air, and condensate, an outlet port for discharging air, and an outlet port for discharging condensate; a one-way valve through which all fluid entering the casing through the inlet opening must flow, the interior of said casing being at all times in 90 free communication with its condensate outlet port, heat-responsive means within said casing for substantially preventing discharge 95 of heated vapor through the air discharge port, and liquid-level responsive means within the casing for substantially preventing discharge of condensate through the air discharge port, the two last mentioned means including a sealed hollow member which serves both as a thermostat and a float.

4. A venting appliance for steam heating 100 systems and comprising in combination; a casing having an inlet port for admitting vapor, air, and condensate, an outlet port for discharging air, and an outlet port for discharging condensate; a one-way valve 105 through which all fluid entering the casing through the inlet opening must flow, the interior of said casing being at all times in free communication with its condensate outlet port, heat-responsive means within said 110 casing for substantially preventing discharge of heated vapor through the air discharge port, the said heat-responsive means including a valve and a sealed hollow member which closes the valve upon rupture of its seal, and liquid-level responsive means within the casing for substantially preventing discharge 115 of condensate through the air discharge port.

5. A venting appliance for steam heating 120 systems and comprising in combination; a casing having an inlet port for admitting vapor, air, and condensate, an outlet port for discharging air, and an outlet port for discharging condensate; a one-way valve through 125 which all fluid entering the casing through 130

- the inlet opening must flow, the interior of said casing being at all times in free communication with its condensate outlet port, heat-responsive means within said casing for substantially preventing discharge of heated vapor through the air discharge port, liquid-level responsive means within the casing for substantially preventing discharge of condensate through the air discharge port, and an adjustable pressure-operated one-way valve for preventing entry of air into the casing through the air discharge port and for selectively controlling the rate of discharge of air through the air discharge port.

6. A venting appliance as set forth in claim 5 and in which the last mentioned valve comprises a gravity disc of selected weight.

7. A venting appliance as set forth in claim 5 and in which the last mentioned valve is operatively connected to a diaphragm responsive to the difference in pressures inside and outside the casing and having a pressure-responsive area greatly in excess of the area of the valve orifice.

8. A venting appliance as set forth in claim 5 in which the last mentioned valve is a compound valve comprising a gravity disc valve member of selected weight for controlling the discharge of air from the air discharge port and a normally open diaphragm valve for insuring that air shall not enter the casing through the air discharge port.

9. A venting appliance for steam heating systems and comprising in combination; a casing having an inlet port for admitting vapor, air, and condensate, an outlet port for discharging air, and an outlet port for discharging condensate; a one-way valve through which all fluid entering the casing

40. through the inlet opening must flow, the interior of said casing being at all times in free communication with its condensate outlet port, heat-responsive means within said casing for substantially preventing discharge of heated vapor through the air discharge port, liquid-level responsive means within the casing for substantially preventing discharge of condensate through the air discharge port, and means for muffling the sound of air discharged from the casing through the discharge port.

10. A venting appliance for steam heating systems and comprising in combination; a casing having an inlet port for admitting vapor, air, and condensate from a radiator, an outlet port for discharging air to the atmosphere, and an outlet port for discharging condensate into a return pipe; a one-way valve for preventing fluid in the casing from flowing through the inlet opening into a radiator, the interior of said casing being at all times in free communication with the return pipe through the condensate outlet port, heat-responsive means within said casing for substantially preventing discharge of heated
